UNITED STATES PATENT OFFICE.

RALPH V. REYNOLDS, OF CHICAGO, ILLINOIS.

CLOTHES-HANGER.

1,301,500.

Specification of Letters Patent. Patented Apr. 22, 1919.

Application filed August 3, 1916. Serial No. 112,974.

To all whom it may concern:

Be it known that I, RALPH V. REYNOLDS, a citizen of the United States, and a resident of the city of Chicago, in the county of Cook and State of Illinois, have invented certain new and useful Improvements in a Clothes-Hanger; and I do hereby declare that the following is a full, clear, and exact description of the same, reference being had to the accompanying drawings, and to the numerals of reference marked thereon, which form a part of this specification.

This invention relates to an improved form of clothes hanger adapted to be removably secured upon a wall or support and having arms thereon formed to permit a number of supplementary coat hangers to be hung thereon in a fixed spaced relation to one another, preventing the same from moving toward each other.

It is an object of this invention to construct a clothes hanger having a plurality of arms formed thereon, each arm having a number of apertures therein affording a means for receiving coat hangers and to hold the same spaced from one another on said arms.

It is also an object of this invention to construct a clothes hanger comprising an apertured base adapted to receive a plurality of sets of tongues therein, said tongues being integrally formed on apertured supporting arms and adapted to be bent at an angle to said arms in back of said base to hold said base and arms together.

It is also an object of this invention to construct a clothes hanger comprising an apertured base adapted to receive a plurality of sets of tongues therein, said tongues being integrally formed on apertured supporting arms and adapted to be bent at an angle to said arms in back of said base to hold said base and arms together.

It is a further object of this invention to construct a clothes hanger having arms thereon adapted for removably receiving a plurality of auxiliary clothes hangers in spaced relation to one another on said arms.

It is furthermore an object of this invention to construct a clothes hanger comprising an armed bracket member having tongues integrally formed thereon and bent at right angles to said member alternately on opposite sides thereof, to afford a means for mounting the bracket member.

It is finally an object of this invention to

construct a clothes hanger simple in construction affording a means for receiving independent clothes hangers thereon in a fixed spaced relation to each other.

60

This invention (in a preferred form) is illustrated in the drawings, and hereinafter more fully described.

In the drawings:

Figure 1, is a side elevational view of a clothes hanger embodying the principles of my invention mounted upon a wall.

Fig. 2, is a front view thereof.

Fig. 3, is a top view thereof, showing the supporting wall in section.

70

Fig. 4, is a sectional view partly broken away taken on line 4—4, of Fig. 1.

Fig. 5, is a front plan view of a modified form of the device.

Fig. 6, is a top plan view thereof, partly broken away.

75

As shown in the drawings:

The reference numeral 1, represents a wall or support upon which is removably mounted by means of screws 2, a clothes hanger comprising a base plate 3, suitably apertured in each corner to receive said screws 2, and having an integral rearwardly turned peripheral flange 4, adapted when mounted to rest against the wall 1, and also affording a chamber 5. Said base plate 3, has centrally formed therein a plurality of alined slots adapted to receive a plurality of sets of tongues 6, projecting therethrough. Said tongues are integrally formed upon the rear edge of a bracket plate cut, stamped or formed to afford a plurality of upwardly inclined arms 7, of different lengths the longest of which is at the top and shortest at the bottom. Each of said arms having a notch 8, formed in the upper outer edge thereof, and a plurality of centrally alined apertures 9, adapted to removably receive the hooks of ordinary coat or clothes hangers in a fixed spaced relation with respect to one another. 100 To hold the bracket plate rigidly secured upon the base plate 3, the tongues 6, already described as projecting into the chamber 5, are alternately bent over at right angles on opposite sides of said bracket plate, against the inner surface of the base plate 3, as clearly shown in Figs. 2 and 4.

In the modified form of the device shown in Figs. 5 and 6, the clothes hanger is constructed of a unitary plate of metal having upwardly inclined integral arms 10, constructed similar to the arms 7. Said plate

105

110

of metal is cut at its rear edge to afford a plurality of tongues 11, each bent outwardly at a right angle to said plate with adjacent tongues disposed on opposite sides of the 5 plate and each provided with a central aperture 12, to permit the clothes hanger to be removably secured upon a wall by means of screws or nails.

I am aware that various details of construction may be varied through a wide 10 range without departing from the principles of this invention, and I therefore do not purpose limiting the patent granted otherwise than necessitated by the prior art.

15 I claim as my invention:

In a device of the class described, the combination with a chambered peripherally flanged base plate having apertures therein, of a unitary plate stamped to provide a plu-

rality of arms integrally connected and of 20 successively shorter lengths from the upper to the lower arm, said arms being vertically aligned and provided with notches and apertures to receive coat hangers, and laterally directed offset lugs all disposed in the same 25 plane at right angles to and integral with said arms, said lugs engaged through said apertured base plate to permit said lugs to seat in said chambered base plate to rigidly hold said arms in position.

In testimony whereof I have hereunto subscribed my name in the presence of two subscribing witnesses.

RALPH V. REYNOLDS.

Witnesses:

CHARLES W. HILLS,
EARL M. HARDINE.
